NONGLARE HEAD LAMP

Eric Olsson, Jersey City, N. J.

Application September 16, 1935, Serial No. 40,740

4 Claims. (Cl. 240—48.4)

This invention relates to new and useful improvements in a non-glare head lamp.

The invention has for an object the construction of a non-glare head lamp which is characterized by a hollow lamp body with its front open, a parabolic reflector within said body, and a transverse glare cutout reflector plate mounted on an annular member engaged on the front edge of said lamp body.

Still further the invention contemplates the construction of the cutout reflector plate on the inner side of said annular member slightly below the center thereof dividing off upper and lower portions and extending upwards at an inclination. Also, the invention contemplates the provision of a translucent glass plate or similar element, mounted across the upper portion of said annular member for cutting out all glaring rays.

Another one of the objects of the invention is to construct the parts so that a conventional lens may be mounted across the front of the hollow body and over the annular member and the translucent plate.

Still further the invention proposes an arrangement whereby a glare director reflector is mounted upon the parabolic reflector and is adapted to direct glaring rays through the lower portion of the annular frame, that is, below the glare cutout reflector plate.

Furthermore, the invention contemplates an arrangement whereby the transverse glare cutout reflector plate may be varied in size for controlling the extent to which the glaring and the non-glaring rays emanate from the device.

Another object of the invention is the construction of a device as described which is simple and durable and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a transverse vertical sectional view of a device constructed according to this invention, certain of the parts being illustrated separated from each other to disclose interior construction.

Fig. 2 is a front elevational view of the device shown in Fig. 1 with the front lens removed.

Fig. 3 is a view similar to Fig. 1 but illustrating a modified construction.

Fig. 4 is a fragmentary sectional view taken on the line 4—4 of Fig. 3.

The non-glare head lamp, according to this invention, comprises a hollow lamp body 10 with a front open end 10^a. A parabolic reflector 11 is mounted within the body and has its edge 11^a terminating in the vicinity of the edge 10^a. A lamp bulb 12 is mounted on the reflector 11 for the illumination of the lamp. An annular member 13 engages across the front edge of the reflector 11 and the lamp body. This annular member supports a transverse glare cutout reflector plate 14 arranged on the inner side thereof slightly below the horizontal center and dividing off an upper section 13^a and a lower section 13^b. The transverse reflector plate 14 extends upwards at a slight angle, as illustrated in Fig. 1. A translucent plate 15 is maintained across the upper portion 13^a of the annular member and is for the purpose of dimming glaring rays. A lens 16 is mounted across the front of the lamp body and serves to hold the annular member in position.

A glare director reflector 17 is mounted upon the parabolic reflector 11 and is for the purpose of directing glaring rays through the lower portion 13^b of the annular member so that the lower portion of the lens is illuminated for illuminating the road.

The hollow lamp body 10 is provided with a bottom boss 10^b upon which a threaded stud 10^c is mounted by which the lamp may be mounted upon a vehicle. The parabolic reflector 11 is of slightly smaller size than the interior compass of the lamp, producing a space 18 therebetween. This space is utilized to house the electric leads 19 for the electric lamp 12. The electric lamp is mounted in a socket 20 mounted upon the parabolic reflector 11. The leads 19 extend to a socket 21 mounted upon the lamp body 10.

The front edge of the body 10 is formed into a flange portion 10^d in which is set a resilient gasket 22. The annular member 13 is formed with a flange portion 13^c adapted to engage the resilient annular member 22 for holding these parts together without permitting the passage of vibration. The translucent plate 15 is held in fixed position by a ring member 23 which is attached upon the inner side of the annular member 13. This ring member corresponds with the shape of the upper opening portion 13^a. The transverse glare cutout reflector plate 14 pref-

- erably is polished for assisting in reflecting the glaring rays at the bottom as desired. The lower area of the parabolic reflector immediately below the cutout reflector plate 14 is of a dull finish. 5 This area is indicated by the distance "A". The purpose is to prevent direct glaring rays from being reflected upwards through the lens of the lamp.

The lens 16 is mounted within an annular 10 shaped frame 24 which is adapted to extend over the annular member 13 and over the edge of the lamp body 10.

A hollow plate 25 is mounted within the frame 24 and is formed with a bulged area 25' adapted 15 to engage in a receiving groove 10' formed parallel to the edge of the lamp body and slightly spaced in therefrom. A set screw 26 engages through the frame 24 and is adapted to abut against the holding element 25' to flex it tightly 20 within the groove by which the lens is fixedly and firmly mounted on the lamp body.

The glare reflector 17 is of a curvature so as to concentrate the glaring light through the opening 13^b of the annular member. It is hinged- 25 ly mounted by a pintle pin 26 upon the parabolic reflector 11. A mechanism is provided to hold the glare reflector 17 in various adjusted positions. This mechanism consists of a stationary bushing 27 mounted through the parabolic re- 30 flector 11 and threadedly connected with a stem 28 having an enlarged head 29 extending through an opening 30 in the lamp body 10. This head 29 is formed with a transverse cut 31 by which the stem may be easily turned. The inner end 35 of the stem 28 connects with a universal joint 32 mounted on the glare director reflector 17. The arrangement is such that the head 29 may be turned in one direction or another direction to adjust the reflector 17 upwards or downwards.

40 In Figs. 3 and 4 a modified form of the invention has been disclosed which is substantially identical to the previous form, the corresponding parts being recognizable by the same reference numerals, but distinguishing in the fact that 45 provision is made for adjusting the transverse glare cutout plate 14' thereof. In this form the plate 14' is composed of a plurality of curved flat sections 14^a, 14^b, etc. These curved sections are normally held in place by screws 34 engaging 50 through the ends thereof and into stationary rails 35 mounted along the walls of the reflector 11.

Thus, sections of the cutout reflector plate may be removed, or other sections added to control the relation between the inner edge of the re- 55 flector cutout plate and the lamp 12.

The operation of the device is as follows:— When the lamp is upon a vehicle and in operation, all of the direct and reflected rays which pass through the upper portion 13^a of the annular member will be dampeden or toned down by the translucent plate 15. The lamp will be readily visible to oncoming vehicles but will not cause the drivers thereof inconvenience by straining their eyes. The lamp directs and reflects glaring rays through the lower portion 13^b of the annular member, and these rays are directed against the ground so as to provide sufficient illumination of the vehicle. The glare director plate 17 may be adjusted to a position in which the greatest number of glaring rays will be directed through the lower portion 13^b of the annular member.

While I have illustrated and described the preferred embodiments of my invention, it is to be understood that I do not limit myself to the precise constructions herein disclosed and the right

is reserved to all changes and modifications coming within the scope of the invention as defined in the appended claims.

Having thus described my invention, what I claim as new, and desire to secure by United States Letters Patent is:—

1. In a non-glare head lamp, a parabolic reflector, an annular member engaged over the front of said reflector and having a top translucent area and a bottom transparent area, a lamp mounted within said parabolic reflector and located above the axis and at an intermediate position between the outer edge and the inner base end of said reflector, a transverse member supported on said annular member and extending 10 rearward from the junction of said translucent and said transparent areas to a position in which its rear edge is adjacent said lamp to form separate passages for the light of said lamp, and a pivotal glare director reflector mounted on the 15 base portion of said parabolic reflector just behind said lamp and adapted to be adjusted to direct the reflected rays of said lamp over the transverse member and through one of said passages or below the transverse member and through the 20 other of said passages.

2. In a non-glare head lamp, a parabolic reflector, an annular member engaged over the front of said reflector and having a top translucent area and a bottom transparent area, a lamp mounted within said parabolic reflector and located above the axis at an intermediate position between the outer edge and the inner base end of said reflector, a transverse glare reflector having a highly polished under side and supported on said annular member and extending upwards at an angle from the junction of said transparent and said translucent areas to divide said parabolic reflector into upper and lower passages 30 so a part of the direct rays of said lamp will 35 pass through the upper of said passages, a glare director reflector mounted on the base portion of said parabolic reflector just behind said lamp to direct other rays of said lamp through the lower of said passages against the highly polished under 40 side of said glare reflector whereby said rays will be reflected at an angle to the road in front of 45 said lamp.

3. A non-glare head lamp, comprising a hollow lamp body with a front opening, a parabolic reflector within said body, a lamp mounted within said parabolic reflector and located above the axis thereof and at an intermediate position between the outer edge and the inner base end of the reflector, an annular member engaged over the front of said reflector and having a top translucent area and a bottom transparent area, a flat transverse plate extending between said lamp and the junction of said transparent and said translucent areas so that its rear edge is adjacent said lamp forming separate passages for the direct light rays of said lamp, a pivotal glare director reflector mounted on the base portion of said parabolic reflector just behind said lamp and adjustable to direct the reflected rays of said lamp over said transverse plate and through one of said passages or below said plate and through the other of said passages, and means for controlling the operative size of said transverse glare reflector plate to control the extent to which the glaring 50 rays of said light will emanate from the device.

4. A non-glare head lamp, comprising a hollow lamp body with a front opening, a parabolic reflector within said body, a lamp mounted within said parabolic reflector and located above the

axis thereof and at an intermediate position between the outer edge and the inner base end of the reflector, an annular member engaged over the front of said reflector and having a top translucent area and a bottom transparent area, a flat transverse plate extending between said lamp and the junction of said transparent and said translucent areas so that its rear edge is adjacent said lamp forming separate passages for the direct 5 light rays of said lamp, a pivotal glare director reflector mounted on the base portion of said parabolic reflector just behind said lamp and adjust- 10

able to direct the reflected rays of said lamp over said transverse plate and through one of said passages or below said plate and through the other of said passages, and means for controlling the operative size of said transverse glare reflector plate to control the extent to which the glaring rays of said light will emanate from the device, comprising rail elements along the sides of said parabolic reflector, and a plurality of adjacent sections removably mounted on said rail elements. 10

ERIC OLSSON.
